(Cl. D26—14)

To all whom it may concern:

Be it known that I, Allan H. Schwing, a citizen of the United States, residing at West Henrietta, in the county of Monroe and State of New York, have invented a new, original, and ornamental Design for Intercommunication Station, of which the following is a specification, reference being had to the accompanying drawing, forming a part thereof.

Fig. 1 is a front elevation view of an intercommunication station, showing my new design;

Fig. 2 is a side elevation;

Fig. 3 is a rear elevation, and

Fig. 4 is a plan view.

I claim:

The ornamental design for an intercommunication station, substantially as shown.

ALLAN H. SCHWING.
